UNITED STATES PATENT OFFICE

LEE DE FOREST, OF NEW YORK, N. Y., AND RICHARD HALPENNY, OF WASHINGTON, DISTRICT OF COLUMBIA, ASSIGNEES, BY MESNE ASSIGNMENTS, TO GENERAL TALKING PICTURES CORPORATION, A CORPORATION OF DELAWARE

LOUD-SPEAKER

Application filed December 1, 1926. Serial No. 151,857.

This invention relates in general to sound producing devices.

One of the objects of the invention is the provision of a novel combination of elements to form a sound reproducing device, particularly adapted for use in large auditoriums, as for instance, in connection with the talking motion picture art.

Another object of this invention is the provision of a sound producing device comprising the combination of a loud speaker horn and a loud speaker cone in a new and novel relation.

A further object of this invention is the provision of a horn of the logarithmic type and a sound reproducing device of the cone type.

A still further object of this invention is the combination of horn and cone vibrating means in such a manner that the sound produced by each is combined and directed from the opening of the horn.

A further object of this invention is the provision of a cone loud speaking unit within the bell of a horn reproducing device to produce a series of sound waves which is the resultant of the individual groups produced by the horn and cone speakers.

A still further object of this invention is the provision of a baffle plate in the mouth of a large horn speaker in back of which is mounted a cone speaker in alignment with an aperture in the baffle plate.

These and many other objects are sought by the combination of elements disclosed as embodying the principles of our invention.

Our invention resides substantially in the combination, construction, arrangement and relative location of parts as will be clearly disclosed in the following specification when taken in connection with the drawings.

Referring to the drawings in which the same reference numerals will be used when possible throughout the several views to indicate the same or similar parts,

Figure 1 is a side elevational view of one form of our invention showing the large end of the horn in cross-section;

Fig. 2 is a similar view to Fig. 1 of a modified arrangement showing a cone

speaker within the bell of the horn speaker showing the bell portion in cross-section taken on line 2-2 of Fig. 3;

Fig. 3 is an enlarged view of the bell end of the construction of Fig. 2 showing a front view thereof;

Fig. 4 is a side view partly in cross-section of the electro-magnetic motive means for the cone speaker.

In the co-pending application, Serial No. 134,781, filed September 11, 1926, by the present Lee de Forest is disclosed an improved loud speaker horn particularly of the logarithmic type adapted for use in motion picture theatres in conjunction with motion picture screens for the production of talking motion pictures.

In this application is disclosed a horn of the logarithmic expansion type especially designed for placement behind the motion picture screen with its large aperture projecting above or at the side of the screen. A similar arrangement is shown in the present application with respect to the special relation of the horn with respect to the screen in combination with a cone type of sound reproducing device.

We have found as disclosed in the present application that sound reproduction from such a type of large horn can be materially improved if we combine a loud speaker unit of the cone type with said horn.

Referring to the drawings in Fig. 1 the motion picture screen of any suitable type and construction is shown at 1 and mounted in back thereof and with its major axis extending vertically is a large sound reproducing device of the horn type having at its smaller end, electro-magnetic means of any suitable construction for converting electric current variations into sound waves. The

particular type of horn disclosed herein, while it may be and is, in its best form of logarithmic type, may however, be of any suitable construction and we only desire to have that form disclosed in the drawings taken in an illustrative sense. The horn is

provided at its other extremity with a large bell having a large opening 4 projecting above the screen or to one side thereof, or even in back of the screen if found desirable.

An aperture of any suitable configuration, such as a circle, is provided in the wall of the bell portion and has mounted in alignment therewith a cone speaker unit. While we have shown the cone speaker mounted directly on the bell, it is, of course, evident that it may be mounted adjacent thereto but out of contact with the bell if desirable. The cone speaker comprises a casing 6 for the electro-magnetic unit supported on brackets 7 and 8 and having the terminals 9 and 10 for the windings of the coils. The cone which is vibrated by the electro-magnetic unit is shown at 11 opening directly toward the aperture in the bell. While we will describe in some detail below, a suitable form of electro-magnetic means for vibrating the cone, we do not desire to be limited to this construction since it is at once evident to any one skilled in the art that there are other known forms of cone speakers.

In Fig. 2, as before, there is shown a screen at 1, a large horn at 2, having the electro-magnetic sound producing device 3 at its smaller end. In this construction and also shown in Fig. 3 there is provided in the opening 4 of the bell, a baffle plate 12 having an aperture 13 at the center in the form of a circle. The baffle plate 12 forms the front wall of a casing 14 mounted in back thereof within which is mounted the cone speaker having as above described the casing 6, terminals 9 and 10 and a cone 11 presenting its free edges towards the aperture. We wish it to be distinctly understood in connection with this form of construction that the casing 14 may be omitted and the cone speaker mounted within the bell and in back of the baffle plate 12 and thereon if desirable.

Referring to Fig. 4, there is shown an electro-magnetic means for vibrating the cone. An iron cup or casing 15 encloses a field winding 18 having the current terminals 19. Mounted on the cone 22, which has the flexible flange 23, is a moving coil 20 having the current terminals 21. This coil freely encircles the core 17 and is disposed in the air gap 16 formed by casing 15. When the field 18 is constantly energized, and the varying current representing the sounds to be reproduced pass through the winding 20, the resulting forces between the fields of these two windings will set the cone 22 in vibration by and in accordance with the varying currents passing through coil 20.

With respect to the baffle plate shown in Figs. 2 and 3, it may be noted that this can be constructed of any suitable material, preferably however, wood. We also desire to point out that the relative proportions of the cone, the baffle plate and the large horn and its bell, may be varied to suit any particular set of acoustic conditions. We have found that the efficiency of a cone type of loud speaker particularly when the cone is of rela-

tively small diameter is greatly increased if said cone is located in the center of the baffle board, the dimensions of which are such as to produce sound waves in the lower band of wave lengths of the sound which it is desired to produce with fidelity.

It will be noted that by the particular arrangements disclosed by us, that the sound from the horn and cone will be admitted directly into the surrounding atmosphere and mingled together as though it were coming from a common source. This is particularly true of the arrangement in Figs. 2 and 3. In the arrangement in Fig. 1 the sound from the cone emerges from the aperture of the large horn and mingles with the sound from the large horn itself to produce in effect a composite wave train from a single source.

It is obvious that such combinations as here shown of a cone and large horn can be obtained in a variety of ways, for example,—the large horn does not necessarily have to have the right angle bend at its orifice but can be straight throughout and the baffle board with the cone loud speaker arranged in the aperture of the horn. The cone speaker could also be mounted on the outside of a horn of the straight type in alignment with a suitable circular orifice cut in one of the flat sides of the horn, preferably near its large open end so that the sound from the cone will first enter into the chamber of the horn similarly to the manner shown in Fig. 1.

We have found that such a combination of two distinct types of loud speakers gives us a distinct advantage in reproduction of sound. By this we mean that the quality of the sound reproduction of such a combination is much better than that from a large horn with a unit at its smaller end having a small diaphragm or from a loud speaker of the cone type, whether it has a cone of small or large diameter. For example, the cone type of speaker, such as illustrated here, wherein the cone is of the order of 6" in diameter is decidedly deficient in the middle tone register. Such a cone will reproduce the lower frequencies down to 150 per second and the higher frequencies from 1,000 or 800 up. However, in the middle range of sound frequencies, it is notably inefficient. On the other hand, the smaller diaphragm type of loud speaker as shown at 3, combined with the logarithmic horn with aperture is somewhat deficient in the higher frequencies but is rich in the middle register frequencies. We have ascertained these peculiarities of these two types of reproducers and have further found that the combination with a horn and cone gives to the resultant sound from the latter alone, an added richness and brilliancy which is very notable.

We have tried various methods of combining these two types of loud speakers and have

found that the ones here illustrated, whereby the sounds from the cone and from the horn actually emerge from the same aperture, are far more satisfactory than where the cone loud speaker with or without a baffle board is merely located near the large aperture of the cone. At the same time the arrangements shown in the drawings permit the use of the logarithmic horn of great flatness which, for reasons already explained in the co-pending application mentioned above, adapts this horn to be attached to the rear of a motion picture screen in such a way as to permit said screen to be raised and lowered among the flies of the theatres without seriously interfering with the battens carrying scenery, drops and the like.

We are, of course, well aware that many changes in the details of construction and even in the relative arrangement of parts will readily suggest themselves to those skilled in the art without departing from the principles of our invention and we do not therefore desire to be limited to the particular constructions disclosed for purposes of illustration, but rather to our idea of the invention as we have defined it in the appended claims.

What we seek to secure by United States Letters Patent is:

1. In a loud speaker, the combination with a logarithmic horn and a cone mounted thereon of separate means for vibrating said horn and cone.

2. In a loud speaker construction, the combination with a logarithmic horn having an aperture in the wall thereof of a cone in alignment with said aperture supported on said horn.

3. In a loud speaker construction, the combination with a horn of a cone mounted on said horn so that the sounds from said cone issue from said horn and separate means for vibrating said cone and horn.

4. In a sound producing construction, the combination with a logarithmic horn having a large bell of a vibratile cone mounted within said bell and separate means of different sound characteristics for actuating said horn and cone.

5. In a sound producing device, the combination with a horn having a bell and a baffle plate in said bell of a vibratile cone mounted on back of said plate.

6. In a sound producing device, the combination with a horn having a bell and a baffle plate in said bell of a vibratile cone mounted on back of said plate and means for vibrating said horn and cone.

7. In a sound producing device, the combination with a horn having a bell and a baffle plate in said bell, having an aperture of a cone mounted on back of said plate and in line with said aperture.

8. In a sound producing device, the combination with a horn having a large aperture

bell and a baffle plate in said opening, said plate being apertured, of an enclosing casing of which said plate forms one wall and a cone speaker in said casing mounted in alignment with said aperture.

9. In a sound producing construction, the combination with a horn having a baffle plate at its mouth, of a cone speaker mounted on said plate.

10. In a sound producing construction, the combination with a horn having a baffle plate at its mouth, an aperture in said plate and a sound producing cone in alignment with said aperture.

11. In a composite loud speaker, the combination with a horn loud speaker having a large bell and an apertured baffle plate in the mouth of said horn of a cone speaker mounted on the back of said plate and within said bell and in alignment with aperture.

12. In a composite loud speaker, the combination with a horn loud speaker having a large bell and an apertured baffle plate in the mouth of said horn of a cone speaker mounted in back of said plate and within said bell and in alignment with the aperture.

In testimony whereof we have hereunto set our hands on this 18th day of November A. D., 1926.

LEE DE FOREST.
RICHARD HALPENNY.
